(57) **CLAIM**

The ornamental design for a surgical staple cartridge, as shown and described.

DESCRIPTION

- 1.1 : Front view of a surgical staple cartridge
1.2 : Back view of the surgical staple cartridge of 1.1
1.3 : Left view of the surgical staple cartridge of 1.1
1.4 : Right view of the surgical staple cartridge of 1.1
1.5 : Top view of the surgical staple cartridge of 1.1
1.6 : Bottom view of the surgical staple cartridge of 1.1
1.7 : Perspective view of the surgical staple cartridge of 1.1
1.8 : Enlarged fragmentary view of 1.1
1.9 : Enlarged fragmentary view of 1.2
1.10 : Enlarged fragmentary view of 1.4
1.11 : Enlarged fragmentary view of 1.7
2.1 : Front view of another surgical staple cartridge
2.2 : Back view of the surgical staple cartridge of 2.1
2.3 : Left view of the surgical staple cartridge of 2.1
2.4 : Right view of the surgical staple cartridge of 2.1
2.5 : Top view of the surgical staple cartridge of 2.1
2.6 : Bottom view of the surgical staple cartridge of 2.1
2.7 : Perspective view of the surgical staple cartridge of 2.1
2.8 : Enlarged fragmentary view of 2.1
2.9 : Enlarged fragmentary view of 2.2
2.10 : Enlarged fragmentary view of 2.4
2.11 : Enlarged fragmentary view of 2.7
3.1 : Front view of another surgical staple cartridge
3.2 : Back view of the surgical staple cartridge of 3.1
3.3 : Left view of the surgical staple cartridge of 3.1
3.4 : Right view of the surgical staple cartridge of 3.1
3.5 : Top view of the surgical staple cartridge of 3.1
3.6 : Bottom view of the surgical staple cartridge of 3.1
3.7 : Perspective view of the surgical staple cartridge of 3.1
3.8 : Enlarged fragmentary view of 3.1
3.9 : Enlarged fragmentary view of 3.2
3.10 : Enlarged fragmentary view of 3.4
3.11 : Enlarged fragmentary view of 3.7
4.1 : Front view of another surgical staple cartridge
4.2 : Back view of the surgical staple cartridge of 4.1
4.3 : Left view of the surgical staple cartridge of 4.1
4.4 : Right view of the surgical staple cartridge of 4.1
4.5 : Top view of the surgical staple cartridge of 4.1
4.6 : Bottom view of the surgical staple cartridge of 4.1
4.7 : Perspective view of the surgical staple cartridge of 4.1
4.8 : Enlarged fragmentary view of 4.1
(Continued)

- 4.9** : Enlarged fragmentary view of **4.2**
4.10 : Enlarged fragmentary view of **4.4**
4.11 : Enlarged fragmentary view of **4.7**
5.1 : Front view of another surgical staple cartridge
5.2 : Back view of the surgical staple cartridge of **5.1**
5.3 : Left view of the surgical staple cartridge of **5.1**
5.4 : Right view of the surgical staple cartridge of **5.1**
5.5 : Top view of the surgical staple cartridge of **5.1**
5.6 : Bottom view of the surgical staple cartridge of **5.1**
5.7 : Perspective view of the surgical staple cartridge of **5.1**
5.8 : Enlarged fragmentary view of **5.1**
5.9 : Enlarged fragmentary view of **5.2**
5.10 : Enlarged fragmentary view of **5.4**
5.11 : Enlarged fragmentary view of **5.7**
6.1 : Front view of another surgical staple cartridge
6.2 : Back view of the surgical staple cartridge of **6.1**
6.3 : Left view of the surgical staple cartridge of **6.1**
6.4 : Right view of the surgical staple cartridge of **6.1**
6.5 : Top view of the surgical staple cartridge of **6.1**
6.6 : Bottom view of the surgical staple cartridge of **6.1**
6.7 : Perspective view of the surgical staple cartridge of **6.1**
6.8 : Enlarged fragmentary view of **6.1**
6.9 : Enlarged fragmentary view of **6.2**
6.10 : Enlarged fragmentary view of **6.4**
6.11 : Enlarged fragmentary view of **6.7**

The evenly-spaced broken lines in the drawings are included for the purpose of illustrating portions of the surgical staple cartridge that form no part of the claimed design. The

dot-dash-dot broken lines in the drawings are included for the purpose of defining the boundary of the claim, it being understood that the region between the dot-dash-dot broken lines and the dot-dash-dot broken lines themselves form no part of the claimed design.
